RAZOR BLADE DISPENSING MAGAZINE

Original Filed Nov. 6, 1941

2 Sheets-Sheet 1

Fig. 7a

FIG. 1

FIG. 2

A cross-sectional view of a cylindrical component, likely a piston or cylinder. The internal structure includes a central piston pin (60) and a piston ring (119). The piston itself is labeled 121. External features include a shoulder labeled 110, a pin labeled 52, and a piston ring labeled 59. The entire assembly is shown within a housing or cylinder body.

RAZOR BLADE DISPENSING MAGAZINE

Zemach Auerbach, New York, N. Y.

Original application November 6, 1941, Serial No. 417,978. Divided and this application September 21, 1943, Serial No. 503,232

3 Claims. (Cl. 206—16)

1

This invention relates to improvements in razor blade magazines. This application is a division of application Serial No. 417,978, filed November 6, 1941, which became Patent Number 2,399,692 on September 21, 1943.

An object of my invention is to provide an improved magazine for double-edged razor blades providing for automatic positioning of the blades and for feeding the blades within a razor, and for retaining the blades in a central position within the magazine so that the cutting edges are out of contact with the magazine walls.

Another object of my invention is to provide a magazine for double-edged razor blades of simple construction having means for spreading the head of a razor.

Another object of my invention is to provide a magazine in which blades can be safely stored and fed from the magazine singly.

For a fuller understanding of the nature and objects of my invention, reference is had to the following detailed description in connection with the accompanying drawings, in which

Fig. 1 is a perspective view of a magazine, showing a razor partly within the magazine and a blade being ejected from the razor and another blade being injected simultaneously.

Fig. 2 is a sectional side view of the magazine, razor and blades shown in Fig. 1.

Fig. 3 is a section taken through line 3—3 of Fig. 2.

Fig. 4 is a top view of the magazine, razor and blades shown in Fig. 1.

Fig. 5 is a top view of the inner member of the magazine shown in Figs. 1 to 4, inclusive.

Fig. 6 is a side view of the inner member shown in Fig. 5.

Fig. 7 is an end view of the inner member shown in Fig. 5.

Fig. 8 is a perspective view of another magazine showing a razor and blade being ejected while another blade is being injected simultaneously.

Fig. 9 is a sectional side view of the magazine, razor and blade shown in Fig. 8.

Fig. 10 is a section taken through line 10—10 of Fig. 9.

Fig. 11 is a top view of the magazine, razor and blade shown in Fig. 8.

Fig. 12 is a top view of the inner member of the magazine shown in Figs. 8 to 11, inclusive.

Fig. 13 is a side view of the inner member shown in Fig. 12.

Fig. 14 is an end view of the inner member shown in Fig. 12.

Referring to Figs. 1 to 6, inclusive, numeral 108 represents a magazine for double-edged razor blades comprising a bottom 109, two sides 110—110, a front 111 and back 112. At the upper portion of magazine 108 there is a pair of longitudinal openings 113 open at the front end and

closed by back 112 at the back end. The back 112 runs to the top of longitudinal openings 113. Front 111 has a horizontal opening 114 for the deposit of used razor blades. Within magazine 108 there is an inner member 115 fashioned of one piece of material comprising a platform 116, two opposed similar sides 117, bent downwardly at right angles at point 118. Attached to the central portion of platform 116 there is a spring member 119 containing notches 120 at each end of said spring member. At the front end of platform 116 there is bent upwardly a U-shaped member 121, the upper ends of which terminate in an oblique angle as shown at 122. At the back end of platform 116 there is a similar U-shaped member 123 bent upwardly, the ends of which terminate in an oblique angle as shown at 124. U-shaped member 123 is slightly higher than U-shaped member 121. Inner member 115 is made to fit snugly within magazine 108 as best shown in Figs. 2 and 3 and is inserted so that the bottom of sides 117 rest upon the inner bottom 109 of magazine 108 and the upper ends 122 of U-shaped member 121 are slightly below the bottom end of inner walls 125 of longitudinal openings 113 of magazine 108, while the upper ends 124 of U-shaped member 123 are slightly above the bottom end of inner walls 125 of longitudinal openings 113 of magazine 108.

In using magazine 108, a stack of blades like blade 60 is placed upon spring member 119, depressing spring member 119 so that the notches 103 rest within U-shaped members 121 and 123 and the uppermost blade presses against the bottom of the inner walls 125 of longitudinal openings 113 with its notches 103 resting within U-shaped member 123. Metal ridge 62 of the bottom blade 60 rests within notches 120 of spring member 119 thus centralizing the blade within magazine 108. Notches 103 of blade 60 fit around the U-shaped members 121 and 123 thus aiding in positioning the blade exactly along the longitudinal medial line of magazine 108.

The razor shown in Fig. 1 is inverted as shown in Fig. 1 so that ridge 62 of the blade within the razorhead 50 abuts ridge 62 of the uppermost blade within magazine 108. The razor is then moved into longitudinal openings 113 so that guards 52—52 enter within longitudinal openings 113. The uppermost blade within magazine 108 ejects the blade within razorhead 50 while the uppermost blade within magazine 108 is injected into razorhead 50. When the razorhead 50 reaches the back wall 112 of magazine 108 the blade formerly within razorhead 50 is completely ejected from the razorhead while the uppermost blade within the magazine 108 is completely injected within the razorhead 50. The used blade 60 which has been ejected can then be dropped into horizontal opening 114 for used blades and the

razorhead 50 is then withdrawn horizontally from magazine 108 with the uppermost blade formerly within the magazine in position within razorhead 50, ready for shaving. The opposed gripping spring members 59 grip the uppermost blade with a greater tension than that exerted by spring member 119 of the magazine so that the uppermost blade can be withdrawn. A similar blade below the blade just withdrawn within razorhead 50 is moved upward by spring member 119 so that it is in position for injecting within the razorhead 50, as above described. The ridges 62 of blades 60 rest one upon another in a stack of blades permitting a uniform space between blades, the U-shaped member 123 holding the blades of the stack in perfect alignment. The space between the blades created by the ridges 62 permits for easier operation.

Referring to Figs. 8 to 13, inclusive, numeral 126 represents a modified magazine for blades comprising a bottom 127, sides 128, front 129 and back 130. At the upper portion of sides 128 there are longitudinal openings 131. In the front 129 there is a horizontal opening 132 for the deposit of used razor blades. Longitudinal openings are formed from sides 128, tops 133—133 and inner sides 134—134. Inner member 135 comprises a platform 136 having two equal sides 137 bent downwardly at right angles at 138. At the central portion of platform 136 there is attached a spring member 139, bent upwardly and having notches 140 at each end. At the front end of inner member 135, a short strip 141 is bent upwardly at right angles, the upper end 142 of which is cut at an oblique angle. At the rear end of inner member 135 there is also a short strip 143, bent upwardly at right angles on the central line of platform 136. The upper end 144 is cut at an oblique angle, strip 143 being slightly longer than strip 141. The inner member shown in Figs. 12, 13, and 14 is made to fit snugly within magazine 126 so that the bottom of sides 131 rest upon the bottom 127 of the magazine 126. The short strip 141 is slightly lower than the bottom of the inner sides 134 of longitudinal openings 131.

In using magazine 126, a stack of blades such as blade 64, is placed upon spring member 139 and depressed, the upper blade resting against the bottom of the inner side 134 of the longitudinal opening 131, short strip 143 resting within notches 107 of blade 64 so that the blade 64 is aligned with the longitudinal medial line of magazine 126.

The razor is inverted with handle 14 upwards with the short edge of blade 64 abutting the short edge of the uppermost blade within the magazine 126. Razorhead 63 is then moved inwardly so that guards 67 of the razor slide within openings 131 of the magazine. The uppermost blade within magazine 126 ejects blade 64 within the razorhead 63, said uppermost blade within the magazine enters razorhead 63 so that when the razorhead completely enters the magazine stopping against back wall 130, the uppermost blade within the magazine is completely within the razorhead 63. The opposed gripping spring members 73 grip the uppermost blade with a greater tension than that exerted by spring member 139 of the magazine so that the uppermost blade can be withdrawn. The ejected blade may then be dropped within horizontal opening 132 for used blades.

It is obvious that various changes and modifi-

cations may be made in the various details of construction without departing from the general spirit of my invention, as set forth in the appended claims.

5 I claim:

1. In a magazine for razor blades of the character described, comprising a bottom, a pair of opposed sides, a back which acts as a stop, a front and a pair of longitudinal channels along the top adjacent said sides and open at the front to receive the guards of a double edged razor, an inner member in the bottom of said magazine having opposed sides bent downwardly forming an inner compartment for used blades and a pair of front and back blade guides bent upwardly parallel to each other, said front guides having inwardly sloping tops adjacent the open ends of said channels, an opening leading into said compartment, spring means within said magazine for maintaining a stack of blades under upward pressure whereby the uppermost blade will enter the razor head upon insertion of said razor head into said magazine.
2. In combination, an inner member with a razor blade magazine, said inner member comprising a one-piece platform forming an upper chamber for new blades and lower chamber for used blades in said magazine, the opposed sides of said inner member bent downwardly at right angles to said platform, a pair of front and back blade guides bent upwardly in parallel relation within said magazine, said guides having tapering tops; a spring member attached to said platform for maintaining an upward pressure upon razor blades within said magazine.
3. In a magazine for razor blades of the character described, comprising a bottom, a pair of opposed sides, a back which acts as a stop, a front and a pair of longitudinal channels along the top adjacent said sides and open at the front to receive the guards of a double edged razor, an inner member adapted to fit within the bottom of said magazine, said member comprising a one-piece platform having opposed sides bent downwardly at right angles to said platform and a pair of front and back blade guides bent upwardly in parallel relation, one pair of said guides having tops adjacent the open ends of said channels and sloping upwardly and inwardly to permit the razor guards to enter the magazine more easily, one of said walls of said magazine having an opening leading into a chamber in the bottom of said magazine created by the downwardly bent opposed sides of said inner member for disposing used blades, a spring member attached to the upper side of said platform for maintaining an upward pressure upon blades in said magazine whereby the uppermost blade will enter the razor guards upon insertion of said 60 razor guards into said magazine.
